GARBAGE CUTTING AND FLUSHING DEVICE

Arvid Bjorklund, Minneapolis, Minn.

Application July 14, 1945. Serial No. 605,104

9 Claims. (Cl. 146—184)

1

My present invention relates to improvements in garbage cutting and flushing devices and is in the nature of an improvement in my pending application of the same title filed September 4, 1944, under Serial No. 552,706.

To the above end, the invention consists of the novel devices and combination of devices hereinafter described and defined in the claims.

In the accompanying drawings, which illustrate the invention, like characters indicate like parts throughout the several views.

Referring to the drawings:

Fig. 1 is a top view of the improved garbage cutting and flushing device;

Fig. 2 is a view partly in side elevation and partly in section taken on the line 2—2 of Fig. 1;

Fig. 3 is a view partly in elevation and partly in transverse section taken on the line 3—3 of Fig. 2;

Fig. 4 is a fragmentary view of the housing in longitudinal central vertical section;

Fig. 5 is a detail view partly in end elevation and partly in transverse section taken on the line 5—5 of Fig. 2;

Fig. 6 is a transverse section taken on the line 6—6 of Fig. 2;

Fig. 7 is a fragmentary view in longitudinal section taken on the irregular line 7—7 of Fig. 6; and

Fig. 8 is a fragmentary view corresponding to Fig. 4, but showing the opposite side of the housing.

The numeral 9 indicates a housing having therein a gear chamber 10, a long horizontally disposed conical rotor compartment 11, and a water conduit comprising an intake section 12 and a discharge section 12', that extends under the chamber 10 and the compartment 11 substantially the full length of the housing 9.

A transverse partition 13, between the chamber 10 and the compartment 11, has therein a large central opening 14 normally closed by a displaceable head 15. Both ends of the housing 9 are open and normally closed by displaceable heads 16 and 17. By removing the heads 16 and 17, access may be had to the interiors of the chamber 10 and the compartment 11, respectively.

A hopper 18 on top of the housing 9 and integral therewith is arranged to discharge garbage fed therein into the compartment 11 at its receiving or inner end portion. An elbow 19 under the bottom of the outer end portion of the compartment 11 and formed as a part of the housing 9 turns downwardly and forms a continuation of

2

the water conduit section 12'. The interior of this elbow 19 affords a flushing chamber 20. In the bottom of the compartment 11 is a port 21 that connects the discharge end portion of said compartment with the flushing chamber 20. A waste pipe 22, attached to the elbow 19, leads to any suitable source of disposal.

Mounted in the compartment 11 is a conical rotor 23 having on its small or inner end a long trunnion 24 that extends through a hole in the head 15 and is journaled in a bearing 25 in the head 16. A packing 26 in the head 16 forms a watertight joint between the chamber 10 and the compartment 11. On the small or outer end of the rotor 23 is a short trunnion 27 journaled in a bearing 28 in the head 17. The rotor 23 and its trunnions 24 and 27 are all in axial alignment with the longitudinal axis of the rotor compartment 11. Adjusting screws 29 in the heads 16 and 17 have conical ends that extend into like seats in the ends of the trunnions 24 and 27 and hold the rotor 23 against end thrusts.

The rotor 23 is driven from an electric motor 30 by connections that include an intermeshing worm 31 and worm gear 32 in the chamber 10. Said worm 31 is carried on a short shaft 33 journaled in the chamber 10 and driven by the armature shaft of the motor 30. The worm gear 32 is carried on the long trunnion 26. A base 34 for the motor 30 also affords a support for the housing 9.

On the periphery of the rotor 23 are two spiral blades 35 and 36 that are ground to sharp edges. These two blades 35 and 36 afford a continuous spiral feed channel 37. The blade 35 is on the inner or small end portion of the rotor 23 directly below the hopper 18 and is relatively coarse.

The blade 36, which forms a continuation of the blade 35, is on the other or large end portion of the rotor 23 and is relatively fine. The distance between the convolutions of the blade 36 progressively decreases from the blade 35 to the outer end of the rotor 23. A transverse passageway in the blade 35 is formed by transverse notches 38, therein. These notches 38, relative to the direction of rotation of the rotor 23, are hook-shaped and produce a cutting and tearing action on the garbage.

Formed with the rotor 23 is a pair of diametrically opposite toothed cutting blades 39 that extend longitudinally of said rotor and transversely through the blade 36. The distance between the teeth in the blades 39 progressively decreases from the inner end to the outer end 55 of the blade 36.

Formed on the inner wall of the compartment 11 are two series of circumferentially spaced longitudinally oblique shearing blades 40 and 41. The shearing blades 40 are directly opposite the blade 35 and the shearing blades 41 are directly opposite the blades 36. The distance between the shearing blades 40 is relatively wide while the distance between the shearing blades 41 is relatively narrow.

In the inner wall of the compartment 11, between the shearing blades 40 and 41, is an annular channel 42. A second annular channel 43 in the inner wall of the compartment 11 extends transversely through the shearing blades 41 at their longitudinal centers. By reference to Fig. 4, it will be noted that the shearing blades 41 terminate at the port 21 and thus leave an annular passageway or discharge chamber 44 in the inner wall of the compartment 11 between the outer ends of the shearing blades 41 and the outer end of said compartment. The port 21 is at the bottom of the passageway 44.

Formed in the side walls of the compartment 11 at the top thereof are two short channels 45 that extend through certain of the shearing blades 40 and lead from the hopper 18 to the channel 42. Two circumferentially extended channels 46, in the side walls of the compartment 11, extend transversely through certain of the shearing blades 40 and lead from the channel 43, just below the lower ends of the channels 45, to a port 47 in the bottom of the compartment 11 at its inner end portion. This port 47 is closed by a screen 48.

A plurality of short knives 49 are attached to the housing 9 by screw-threads and project radially from the side wall of the compartment 11 on the downwardly moving side of the rotor 23. These knives 49 are spaced apart longitudinally of the compartment 11 directly below the hopper 18 and extend into the section of the feed channel 37 formed by the blade 35. The knives 49 are positioned with their cutting edges uppermost.

A pair of pins 50 having screw-threaded engagement with the rotor 23 project radially into the channels 42 and 43. The ends of the pins 50 are cut square to produce a cutting and tearing action. On the outer end of the rotor 23 is a stirring pin 51 that prevents garbage from clogging the discharge space between the outer ends of the head 17 and the rotor 23.

Water is delivered into the water conduit section 12 through a bossed opening 52 in the respective end of the housing 9 from a pipe 53 attached to said housing by screw-threads and leading from any suitable source of supply under pressure. The water conduit section 12, under the bottom of the gear chamber 10 first curves downwardly from the inlet opening 52, then upwardly and tangentially to the port 47. A port 54 connects the conduit section 12, at its delivery end, to the conduit section 12' at its intake end. This port 54 is spaced materially above the bottom of the water conduit section 12'.

A branch water pipe 55 leads from the water pipe 53 and its discharge end portion has threaded engagement with the housing 9, at an opening 56, that leads into the channel 42 at the lower end of the respective channel 45.

A valve 57 interposed in the pipe 53 and to which the branch pipe 55 is attached will be of a type to permit water to flow to either the water conduit section 12 or through the branch pipe 55 or both. On the inner end of the rotor 23 is a disk-like head 58 that prevents garbage from ac-

cumulating between the partition 13, head 15 and the respective end of the rotor 23.

Operation

The operation of the above described garbage cutting and flushing device may be briefly described as follows: Garbage placed in the hopper 18 will be precipitated onto the blade 35 and into the conveying or feed channel 37. This garbage is first acted upon by the rotating cutting blade 35 and the co-operating stationary shearing blades 40 and coarsely cut. During this operation, the blade 35, or the hook-like notches 38 thereon tear the mass of garbage apart and further disintegrate the same. Bones or other objects lodged on the knives 49 will be engaged by blade 35 at its hook-like notches 38 and broken into relatively small parts. The relatively short radius of the coarse blade 35 produces powerful cutting and crushing action on the coarse garbage, bones, etc., as the same is fed thereto from the hopper 18.

From the blade 35 the garbage being conveyed in the channel 37 is fed to the rotating cutting blade 36 and the cooperating stationary shearing blades 41 and progressively cut finer as it is conveyed to the passageway chamber 44. The pins 50 rake and cut corn silk and other materials between the rotor 23 and the shearing blades 41.

During the operation of the device, water in the conduit section 12 is discharged in part through the port 47, into the compartment and reduces the garbage being cut to a fluid condition. The residue of water in the conduit section 12, which is the major portion thereof, is discharged through the port 54 and into the inclined conduit section 12' where the same flows to the flushing chamber 20, and flushes the disintegrated garbage precipitated from the passageway 44 through the port 21 and into said chamber.

The channels 42, 43, 45 and 46 facilitate the flow of water and fluid garbage to the compartment 11 and the commingling of the water and garbage. In case more water is discharged into the compartment 11 through the port 47 than will escape past the rotor 23 to the chamber 44, said water will back up in the compartment 11 and flow through the channels 45 and 46 to the port 47 where the same will escape into the conduit section 12' through the port 54. The screen 48 prevents garbage, bones, etc., from escaping through the port 47 into the water conduit section 12' and be conveyed to the waste pipe 22 where the same is liable to clog said pipe.

Due to the conical form of the compartment 11 and the rotor 23, the blades 35 and 36 may be sharpened and the rotor 23 axially adjusted in the compartment 11 to compensate for the cut made thereon.

After the garbage is disposed of, the device, while still operating, may be cleansed by operating the valve 57 for the flow of water through the branch pipe 55 and into the compartment 11 where the water is splashed by the rotor in all directions.

The drawings illustrate a commercial form of the invention, but it will be understood that the same is capable of certain modifications as to details of construction, arrangement and combination of parts within the scope of the invention herein disclosed.

What I claim is:

1. A device of the character described comprising, a housing provided with a rotor compartment having shearing blades on its interior

walls disposed axially of said compartment, a rotor in said compartment provided with a spiral cutting blade cooperating with said compartment shearing blades, a feed hopper in communication with the compartment at a point adjacent one end of the rotor, the other end of the rotor terminating at a spaced distance from the other end of said compartment to form a discharge chamber in said compartment end, a water conduit in communication with the rotor compartment at a point beneath the feed hopper, a continuation of said water conduit extending to a point beneath the compartment discharge chamber, the compartment discharge chamber provided with a discharge port opening into the said conduit continuation, the conduit continuation being provided with a discharge end, means for supplying water to the conduit, and means for rotating the rotor.

2. A structure as defined in claim 1 wherein, an annular channel is formed in the wall of the rotor compartment transversely through the shearing blades thereon, those shearing blades beneath the feed hopper being cut away obliquely to form a passageway extending from the said annular channel to the feed hopper, and a second obliquely formed passageway extending between said annular channel and the juncture of the water conduit with the compartment.

3. A structure as defined in claim 1 wherein, an annular channel is formed in the wall of the rotor compartment transversely through the shearing blades thereon, those shearing blades beneath the feed hopper being cut away obliquely to form a passageway extending from the said annular channel to the feed hopper, a second obliquely formed passageway extending between said annular channel and the juncture of the water conduit with the compartment, and a plurality of pins carried by the rotor to travel in said annular channel.

4. A structure as defined in claim 1 wherein, an annular channel is formed in the wall of the rotor compartment transversely through the shearing blades thereon, those shearing blades beneath the feed hopper being cut away obliquely to form a passageway extending from the said annular channel to the feed hopper, a second obliquely formed passageway extending between said annular channel and the juncture of the water conduit with the compartment, a plurality of pins carried by the rotor to travel in said annular channel, and second water supply means for supplying flushing water directly into said annular channel.

5. A structure as defined in claim 1 wherein, that portion of the rotor beneath the feed hopper is provided with a plurality of hook-like notches formed transversely through the spiral cutting blades thereof, that portion of the wall of the rotor compartment beneath the feed hopper being provided with a plurality of knives having cutting edges, said knives being so spaced longitudinally

of the compartment as to coincide with the depths between the spiral blades of the rotor, the cutting edges of said knives being opposed to the direction of rotation of the rotor, and the hook-like notches having their open sides facing in the direction of rotation of the rotor.

6. A structure as defined in claim 1 wherein, a stirring pin is secured to the discharge end of the rotor for rotation therewith in the discharge chamber of the compartment.

7. A structure as defined in claim 1 wherein, a screen covering is provided for the water conduit at its juncture with the rotor compartment, and a stirring pin is secured to the discharge end of the rotor for rotation therewith in the discharge chamber of the compartment.

8. In a device of the character described consisting of a housing having a rotor compartment provided with interior shearing blades, a rotor in said compartment having a spiral cutting blade cooperating with the shearing blades, a feed hopper communicating with the compartment at one end of the rotor, a discharge outlet at the other end of the rotor, a means for supplying flushing water to the rotor compartment comprising, an upwardly and rearwardly inclined water conduit communicating with the rotor compartment at a point beneath the feed hopper, an overflow port in said conduit immediately beneath the juncture thereof with said compartment, a continuation of said conduit extending from the overflow port to the housing discharge outlet, and means for supplying water to said water conduit for the purpose described.

35 9. A structure as defined in claim 8 wherein, an annular channel is formed transversely through the shearing blades of the compartment intermediate the length thereof, and a passageway extending obliquely through the shearing blades providing communication between the annular channel and the said water conduit.
